UNITED STATES PATENT OFFICE.

WALKER W. McCARROLL, OF ARLINGTON, NEW JERSEY.

MACHINE FOR RECTIFYING ELECTROTYPE.

1,109,855.

Specification of Letters Patent.

Patented Sept. 8, 1914.

Application filed January 9, 1911. Serial No. 601,585.

To all whom it may concern:

Be it known that I, WALKER W. McCARROLL, a citizen of the United States, residing in Arlington, county of Hudson, and State 5 of New Jersey, have invented an Improvement in Machines for Rectifying Electrotype, of which the following is a specification.

This invention relates to machines for rectifying electrotype and has particular reference to improvements in the hammer mechanism of said machines.

Machines for rectifying electrotype plates are known to the art and comprise generally 15 a bed plate upon which the electrotype plate rests during the operation, a hammer mechanism for delivering blows upon the back of the plate at such places which require raising, that is, rectifying to produce a perfect 20 impression, and a suitable abutment suspended above the bed plate and adapted to be pressed down on the latter to furnish the necessary resistance against the operation of the hammer. This latter operates on suitable 25 tools located in the bed plate and which are adapted to be brought into suitable position with respect to the hammer, the position of which is fixed. Between each blow the abutment member is raised to permit 30 the operator to adjust the electrotype to receive the blows of the hammer in the proper places.

It is one of the objects of this invention to improve upon the construction and design 35 of the machine so as to enlarge and increase its usefulness and to enable the operator to give his entire attention to the work of rectifying by providing suitable automatic mechanisms tending to relieve the 40 operator of the necessity of constant attention to the operating parts.

Other objects of the invention are to cure the existing machines of various errors inherent in their construction.

45 Other objects will appear as this specification proceeds.

To this end the invention is embodied in a machine for rectifying electrotype such as set forth in the following specification 50 while reference is had to the accompanying drawings in which:

Figure 1 is a front elevation of a machine embodying my invention. Fig. 2 is a detail view of means for causing the abutment to 55 operate in a hammer-like manner. Fig. 3 is a view looking from the right in Fig. 1

with parts in section and parts omitted. Fig. 4 is a detail sectional view of the tool holder and the abutment above the same. Fig. 5 shows a modified construction of the 60 abutment. Fig. 6 is a detail view of parts of the abutment operating mechanism and Fig. 7 is a detail view of parts of the means for adjusting the operation of the hammer.

Referring to the drawings the reference 65 numeral 8 represents a suitable frame which carries a level bed plate 9 for the support of the electrotype. This latter is placed over the center of the bed plate in which there is supported a tool holder 10 containing various shaped tools 11 normally held flush with the bed plate by springs 12. The tool holder is rotated by means of a gear 13. A detailed description of the tools and the 70 tool holder is not necessary as the same are 75 not new; sufficient for this disclosure is it to say that the tools are preferably arranged in a circle so that by rotation any one of them may be brought directly over the hammer 14. This latter is in the form of a 80 steel bar held upward by a strong spring 15 and suitably guided in the frame. The upper end of the spring acts against a collar 16.

The hammer is operated by means of a 85 vertically reciprocating bar 17 guided in a fork shaped guide piece 65 and having a cam 18 which engages a small roller 19 on the hammer release 20. A collar 21 is fast 90 on the bar 17 and adapted to engage the collar 16 aforesaid to compress the spring 15 to operate the hammer. A spring 22 keeps the bar 17 in engagement with the roller 19.

The bar is reciprocated by means of an eccentric 23 fast on the driving shaft 24 to 95 which power may be applied by any suitable means. It will be understood that during operation the vertical bar 17 is continuously reciprocated. The cam 18 sliding along the roller 19 keeps the collar 21 100 from engaging the collar 16 and the hammer remains stationary. When, however, the hammer release 20 is pulled down a certain distance, the spring 22 pulls the bar to the right and the collar 21 catches the collar 16 and compresses the spring 15 until the cam 18 again engages the roller 20.

105 Thereby the bar 17 is again pushed to the left, the collars are disengaged and the hammer is thrown strongly upward by the 110 spring 15 and a blow is delivered on the tool immediately above the hammer. The

farther down the hammer release is moved the longer the collars are in engagement and the stronger is the blow.

The hammer release is operated by means of a treadle 25 actuated by a pivoted foot piece 26. The treadle is loose on a shaft 27 and carries a pin 28 engaging a slot 29 in the rod 30 which carries the hammer release 20. A spring 31 normally forces the release upward.

To the shaft 27 there is secured a treadle shoe 32. The shaft may be rotated to adjust the treadle shoe by means of the arm 33 and lever 34. This latter passes through a casing 35 having a pin 36 adapted to engage notches 37 on the lever 34. A spring seated stop 38 keeps the lever 34 up against the pin 36.

Thus the lever 34 may be set with relation to the casing 35, which is fast to the frame 8, and hence the treadle shoe may be adjusted into given positions away from the treadle, as will be understood. The treadle can only be depressed so far down till it abuts the shoe. By setting the lever 34 in a given position the operator is relieved from the necessity of constantly watching the treadle to secure the proper kind of a blow. By this means, once the lever 34 is set, the operator simply keeps the treadle down on the treadle shoe. A spring 39 assists in moving the treadle upward.

Above the bed plate there is suspended the abutment 40 comprising a frame 41 supported by a ball and socket joint 42 from the vertical shaft 43 which carries a weight 44 and a bevel gear 45 which engages the bevel gear 46 on a shaft 47. This latter carries at its outer end a bevel gear 48 and a hand-wheel 49. A vertical shaft 50 carries a bevel gear 51 meshing with the gear 48, and a gear 52 meshing with a gear 53 which latter is in engagement with the tool holder gear 13 aforesaid.

The abutment frame 41 is formed with a ring 54 to which is secured a block frame 55 by screws 56. The frame 55 contains a block of glass 57 having marks 58 thereon corresponding to the position of the tools 11. A gasket is interposed between the frame 55 and ring 54 as shown, and interposed between the latter and the glass block there is a leveling ring 59 adapted to be adjusted by screws 60. A cushioning member 61 in the form of a ring of rubber, fiber or similar material is secured to the frame 55.

It is of the greatest importance that the lower surface of the glass block be perfectly and absolutely level when the abutment is brought down on the electrotype, or the blows on the latter will spoil it. It is also necessary that the block has sufficient backing against the blow. Hence, when the block is faulty, the leveling ring 59 is adjusted as shown in Fig. 5 to level the lower

surface of the glass and also to form a backing. In this latter figure I have shown rubber tipped screws 62 as a modification of the ring 61.

The abutment 40 is reciprocated vertically by means of an oscillating arm 63 pivoted at 64 on the frame 8 and suitably engaging the vertical shaft 43 which forms a part of the abutment and to which the gear 45 is secured. Through the other end 66 of the arm 63 passes a rod 67 the lower end of which carries two cam rolls 69, 69 between which rotates a cam 68 fast on the driving shaft 24. As the cam rotates the rolls 69 are raised and lowered and the rod 67 reciprocated vertically. The lower end of the rod 67 is of course slotted to permit the shaft 24 to pass through it, as is obvious. A spring 70 adjustable by nuts 71 forces the end 66 upward, and by means of nuts as 72 this end of the arm follows the downward movement of the rod 67.

Means are provided whereby the abutment remains stationary until the treadle is depressed even after the power has been applied to rotate the driving shaft. To this end there is journaled in the frame 8 a small shaft 73, Figs. 1 and 6, having a cam 74 formed in a recess in said shaft. On the latter, at the point where the cam is, rests a stop 75. Above the latter there is an adjusting screw 76 carried in the arm 63. Normally the stop 75 is kept upwardly by the cam as shown in Fig. 6 and this prevents the oscillation of the arm 63. When the cam is turned horizontally the stop 75 drops down thereon and the arm 63 commences to oscillate to reciprocate the abutment 40. This shaft 73 is rotated to lower the stop 75 by means of a cable 77, see Fig. 1, attached to the aforesaid pin 28 in the treadle. The upper end of the cable is attached to a disk 77' secured to the front end of the shaft 73. It will be observed that the depression of the treadle and the pin 28 immediately causes the stop 75 to be lowered so that the abutment is ready to co-operate with the hammer as soon as the hammer release is operated.

From the foregoing description the normal operation of the machine can be understood and is as follows: The rotation of the driving shaft 24 operates the reciprocating bar 17 but the other parts of the machine remain stationary. When the operator is ready to work on a plate, the treadle is depressed whereby first the stop 75 is lowered and the abutment commences to reciprocate and secondly the hammer release is operated to cause the hammer to act on the tools. The parts are so timed that the abutment is raised slightly after each blow to permit the operator to adjust the electrotype between blows.

Before commencing to rectify the electro-

type it is very often necessary to level the plate by blows on the top of the same along the edges thereof. For this purpose I provide means for causing the abutment to descend sharply in a hammer-like manner while the normal downward motion of the abutment is in the nature of a pressure applied to counteract the hammer blows. To this end I provide the following mechanism:

10 To the rear end of the small shaft 73 is secured a pulley segment 79, see Fig. 2, to which is attached a cable 80 secured to a sliding catch 81 guided in a boss 82 on the frame 8. An expansion spring 83 tends to force the catch leftward in Fig. 2. The catch is provided with a dog 84 adapted to engage another dog 85 on the end of a catch 86 pivoted at 87. The arm 63 carries an adjustable screw 88 adapted to trip the catch 86 to disengage the dogs 84 and 85 as will be understood from the drawing. A spring 89 keeps the dog 85 in engagement with the dog 84. An eccentric 90 is provided to depress the catch 86 to disengage the dogs 25 manually when desired, which is during the normal operation of rectifying, when this device for operating the abutment as a hammer is inoperative, except that the expansion spring 83 assists in rotating the shaft 30 73 in a clockwise direction to raise the stop 75, the shaft 73 being rotated in anti clockwise direction by the depression of the treadle.

When, however, it is desired to operate 35 the abutment as a hammer the eccentric 90 is turned as shown in Fig. 2. It will be seen from this figure that the engaged dogs 84 and 85 prevent the rotation of the shaft 73 except when the stud 88 is moved downward by the oscillations of the arm 63 to trip the catch 86 which of course happens when the abutment 40 is up. The moment the dogs are disengaged the shaft 73 is turned, by the depression of the treadle, to 45 lower the stop 75 permitting the abutment to descend with a blow on the electrotype plate. But as soon as the abutment has delivered the blow and again ascends the expansion spring 83 forces the catch 84 leftward to engage the catch 85 to again prevent the immediate descent of the abutment until the releasing screw 88 has caused the disengagement of the dogs.

It will be noted that the hammer action 55 of the abutment only occurs each time the treadle is depressed. When the abutment is operated as a hammer the treadle is depressed only far enough to release the stop 75, but not far enough to release the hammer. The treadle shoe being set accordingly. The ring 61 prevents injury to the glass block which may be caused as the abutment descends immediately after the depression of the treadle. To prevent a sudden downward motion of the abutment there is pro-

vided on the cable 77 a collar 92, seen only in Fig. 1, which is adapted to engage a forked member 93 adjustably carried by the arm 63 as shown.

The first downward motion of the abutment occurs simultaneously with a leftward movement of the collar 92 on the cable 77 when the treadle is depressed as understood, but the fork 93 is so adjusted that it prevents the passage of the collar 92 until the second downward oscillation of the right end of the arm 63, when the collar 92 will have passed beyond the fork 93. Thus this device acts as a safety for the glass block 57, because the abutment can not descend until the shaft 73 has been completely turned, and the shaft 73 can not be completely turned until after the abutment is descending the second time. In other words, the first descending movement of the abutment is not effective but the shaft 73 is permitted to be turned completely first to free the stop 75.

In order to remove the dust caused by the process of rectifying, I provide a semi-circular blow pipe 94 supplied from a suitable pump, not shown, and suitably secured to the frame a slight distance above the bed plate to permit the electrotype plate to be moved under the pipe, which latter is provided with apertures 95, Fig. 3, through which a blast is directed over the electrotype to remove the dust.

The above is thought to fully explain this invention and the operation thereof, the main advantages of which are that thereby a separate operation of the abutment as a hammer and a more nearly automatic operation of the whole machine is made possible, hence a more perfect rectifying of the electrotype plates.

The invention is susceptible of changes in the details and I claim all such as properly come within the legitimate scope of the invention as set forth in the claims.

Therefore I claim:

1. The combination of a bed plate for supporting an electrotype plate, tools in said bed plate, a hammer for operating on the said tools, an abutment supported above the latter, means for operating said hammer and abutment in unison to rectify the said electrotype plate and means for operating said abutment independent of the operation of the said hammer.

2. In a machine of the character described the combination of a bed plate for supporting an electrotype, tools in said plate, a hammer below said tools, means for operating said hammer, an abutment above the tools, means for operating said abutment, a treadle for actuating both of the said operating means, a treadle shoe and means for adjusting the latter to limit the movement of the said treadle.

3. In a machine of the character described the combination of a bed plate for supporting an electrotype, means for operating on the latter to rectify the same, a treadle for actuating the said means, a treadle shoe for regulating the movements of the treadle, an operating lever for said treadle shoe and locking means for locking the said lever in a predetermined position.
10. 4. In a machine of the character described the combination of a bed plate for supporting an electrotype, a hammer, means for operating the latter to rectify the said electrotype, an abutment for exercising a pressure against the operation of the said hammer and a yielding member secured to the abutment for cushioning the latter as the same is pressed against the said electrotype.
15. 5. In a machine of the character described the combination of a bed plate for supporting an electrotype, a hammer, means for operating the latter to rectify the said electrotype, an abutment for exercising a pressure against the operation of the said hammer and a ring contained within the said abutment and means for adjusting the said ring to level the lower surface of the abutment.
20. 6. In a machine of the character described the combination of a bed plate for supporting an electrotype, a hammer, means for

operating the same to rectify the said electrotype, an abutment supported above said bed plate, said abutment comprising a frame, a glass block in said frame, adjustable means for leveling the lower surface of the said glass block, means for reciprocating said abutment, a treadle for actuating both of the said operating means, a treadle shoe and means for adjusting the latter to limit the movements of the said treadle.

7. The combination of a bed plate for supporting an electrotype, a movable abutment supported above the said bed plate, a lever for reciprocating said abutment, a member for keeping said lever immovable, a rotatable cam for supporting the said member, means for normally keeping said cam in a given position and means for rotating the cam to release the said member and for operating the said lever.

8. In a machine for rectifying electrotype plates the combination of rectifying tools for rectifying the plate from below, a glass block adapted to operate on the said plate from above and having a smooth lower surface bearing marks to indicate the positions of the said tools below and means for operating the latter and the said glass block.

WALKER W. McCARROLL.
